REGULATOR

Christian A. Sorensen, Oakland, Calif.

Application June 14, 1941, Serial No. 398,172

3 Claims. (Cl. 50—35)

My invention relates to regulators in general, and more particularly to regulators for controlling the flow of gas such as butane, to internal combustion engines.

In the operation of internal combustion engines, great economies have been realized through the use of cheap fuels instead of gasoline. One such fuel, which has enjoyed widespread use, particularly in farm and rural districts, is the gas known as butane. By reason of its gaseous nature, at normal temperatures and pressures, it is, however, somewhat less convenient to handle than a liquid fuel such as gasoline. It is normally supplied to a vehicle tank in liquid phase, and through evaporation, gradually enters into the gaseous state and develops considerable pressure in the vehicle tank.

Because of this high pressure developed in the fuel tank, due to the generation of the gas, it becomes necessary to effect a positive sealing of the tank supply upon shutting down of the engine; and during operation of the engine, to regulate the supply thereto in accordance with the demands made by the engine. Regulators have accordingly been provided for the purpose, but these are based upon the use of a flexible diaphragm, and are sufficiently complex in structure and manufacture as to require the use of a service-man in the adjustment and repair thereof. Unless an engine be also equipped with an emergency gasoline supply system, failure of one of these diaphragm regulators is apt to leave a user stranded and render his vehicle inoperative over an extended period of time, until such regulator can be serviced. This would be particularly inconvenient in the case of a farmer operating a tractor in the cultivation of extensive areas.

Among the objects of my invention are—

- (1) To provide a novel and improved regulator;
- (2) To provide a novel and improved regulator for internal combustion engines running on butane or some corresponding gaseous fuel;
- (3) To provide a novel and improved regulator of such few parts and rugged construction as to enable its adjustment and repair a simple matter;
- (4) To provide a novel and improved regulator utilizing a cheaply obtainable and easily replaced standardized valve assembly, whereby the most delicate part of the regulator may quickly and easily be replaced and at the cost of but a few cents.

Additional objects of my invention will be

brought out in the following description of the same taken in conjunction with the accompanying drawing wherein—

Figure 1 is a view in section through one embodiment of my invention;

Figure 2 is a view in section, taken along the line 2—2 of Figure 1;

Figure 3 is a fragmentary view in section, illustrating a modification of my invention;

Figure 4 is a view looking down on the valve assembly of Figure 3.

Referring to the drawing, the device of my invention comprises a cylinder 10, the ends of which are internally threaded to receive closures which constitute end walls 13 and 15 of the cylinder. One of these closures, 13, is provided with a small vent opening 17, permitting the passage of air therethrough.

Within the cylinder, I provide a piston which includes a piston head 19 mounted at one end of a piston rod or stem 21 which extends centrally through the vented closure 13. This piston rod carries a spring 23 between the piston head and the vented closure, and another spring 25 preferably of conical shape, on the protruding end of the rod. A washer 27 disposed on the rod adjacent the end of the conical-shaped spring, and a pair of nuts 29 threaded to the end of this rod enable adjustment of the piston to determine its normal position in the cylinder with both springs 23 and 25 under compression. The piston head 19 includes a sealing cup 31 of leather, rubber or other suitable material clamped between a pair of supporting washers 33 and 35, with the cylindrical wall 37 of the cup directed toward the vented end 13 of the cylinder. The working face of the piston may thus be considered as the side facing the end wall 15 of the cylinder, with which it forms a chamber 39.

The end wall 15 is provided with an opening 41 disposed to one side of the center of the end wall, and surrounded on the outer surface of the end wall by a hollow internally threaded boss 43 adapted to receive a nipple or feed line 45 preferably for connection to the intake manifold of an engine.

Centrally of the same end wall, there is another opening 47 which is surrounded by a hollow internally threaded boss 49 and 51 on both the inner and outer surface of the end wall. The outside boss 49 is adapted to receive a feed line 53 extending from a fuel tank (not shown), to carry the gaseous fuel to the cylinder. The interior boss 51 is adapted to receive a valve assembly 55, preferably such as is customarily em-

ployed for bicycle or automobile tires, and known on the market as a "Schrader" valve.

Such valve assembly comprises a casing 57 which threadedly receives an arrangement of a valve seat 59 and valve 61 that can be removed as a unit. The valve is usually possessed of a valve stem 63 which protrudes slightly beyond the open end of the casing.

After the device has been assembled in the manner indicated, the piston is adjusted so that the piston head 19 occupies a normal rest position, just slightly spaced from the protruding valve stem 63 of the valve assembly.

The operation of the device is quite simple. As the engine is cranked for starting, air is absorbed from the piston chamber 39 on each suction stroke of the engine, to gradually develop a condition of partial vacuum in the chamber. The existence of atmospheric pressure behind the piston head 19 results in exposing the piston to a differential pressure created by the exhaustion of air from the chamber 39, and the piston will gradually move forward toward the valve assembly 55. As the degree of evacuation increases, the piston will ultimately press against the valve stem 63 and gradually open the valve, thereby admitting gas from the supply tank to the engine by way of the chamber 39. Upon ignition occurring, the average rate of consumption of gas, at various speeds of the engine, is sufficient to maintain an average pressure in the chamber 39, lower than atmospheric pressure, thereby holding the piston against the valve stem, whereby the valve will remain open. Between suction strokes at slow speeds and particularly at idling speed of the engine, when the inrushing gas may tend to momentarily raise the pressure in chamber 39 and render conditions favorable for withdrawal of the piston to shut off the valve, a chattering of the piston would occur at such slow speeds, were the piston free to withdraw instantly. To prevent this, the vent 11 is made quite small so that, although still sufficient to maintain atmospheric pressure behind the piston, it is nevertheless small enough to preclude rapid escape of air, and thereby establishes an air cushion behind the piston. Such air cushion, in addition to discouraging any sudden withdrawal of the piston, will also serve to spread the sealing cup 31 against the cylinder wall, and thereby increase its resistance to movement toward its normal rest position.

To assure that the piston will not completely block the valve passage, should the piston head 19 move far enough forward to rest against the end of the valve assembly casing 57, I contemplate notching the end of the valve casing so that there will always exist an opening or plurality of openings 65 from the casing for the flow of incoming gas when the valve is open.

As a further safeguard to the prevention of chattering of the piston 19 at idling speed, I may provide a bracket 67 on the vented end 13 of the cylinder, which has a laterally disposed portion 69 facing the exposed end of the piston rod 21. This bracket is adapted to carry an adjusting screw 71 which may be threaded through the bracket and carries a coil spring 72 which bears against the nuts 29 at the end of the piston rod. Such adjustment will damp any tendency which might exist or develop on the part of the piston to oscillate under the stimulation of the springs 23 and 25.

As a modification of the embodiment disclosed in Figure 1, I contemplate substituting for the

single valve assembly, a multiple valve assembly 73, with the valve stems 63 extending different distances in the direction of the piston head 19. The assembly may be conveniently formed by soldering two or three of the valve assemblies of Figure 1 into a common cylinder 75, and so adjusting the casings that the valve stems 63 will occupy different positions with respect to the piston. Or in the event that the stem of a standard valve assembly is too short to permit of such an arrangement, the valves may be provided with valve stems of different lengths to serve the same purpose. A plural valve assembly as disclosed in Figures 3 and 4, will enable one with greater accuracy, to supply the engine with fuel at a rate more commensurate with the requirements of the engine at different speeds or loads, for it will be apparent that as the piston moves forward, the distance to which it moves being a function of the engine speed, the valves will be opened in succession so that under conditions when the engine requires its greatest supply of fuel, the piston will have moved forward sufficiently to have actuated all of the valves.

The regulator, while it has been described as such for use in controlling and regulating the supply of gas to an internal combustion engine, is nevertheless capable of being modified or altered to adapt it to different uses, without departing from the spirit of my invention. Therefore, while I have disclosed my invention in some detail, I do not desire to be limited in my protection thereto, except as may be necessitated by the appended claims.

I claim:

1. As an article of manufacture, a regulator comprising, a cylinder having end walls; a piston in said cylinder facing one of said end walls to define a chamber, and having a piston rod extending axially of said cylinder and through the other of said end walls; a pair of springs surrounding said piston rod, one within said cylinder and one outside said other end wall; an adjusting nut on the extremity of said piston rod, adapted for altering the normal rest position of said piston in said cylinder under simultaneous compression of said springs; an opening through that end wall facing said piston, through which gas in said chamber may be evacuated; another opening through said same end wall; and a self-contained valve assembly disposed in said last-mentioned opening, said valve assembly including a tubular casing extending toward said piston and a valve in said casing having a valve stem protruding from said casing to within a short distance of said piston, said casing being slotted at the piston end thereof.

2. As an article of manufacture, a regulator comprising, a cylinder; a closure for each end of said cylinder; a piston in said cylinder facing one of said closures to define a chamber, and having a piston rod extending axially of said cylinder and through the other of said closures; a pair of springs surrounding said piston rod, one within said cylinder and one outside said other closure; an adjusting nut on the extremity of said piston rod, adapted for altering the normal rest position of said piston in said cylinder under simultaneous compression of said springs; an eccentrically disposed opening through that closure facing said piston, through which gas in said chamber may be evacuated; another opening through said same closure; and a self-contained valve assembly disposed in said last-mentioned opening, said valve assembly including a

tubular casing extending toward said piston and a valve in said casing having a valve stem protruding from said casing to within a short distance of said piston.

3. As an article of manufacture, a regulator comprising, a cylinder; a closure for each end of said cylinder; a piston in said cylinder facing one of said closures to define a chamber, and having a piston rod extending axially of said cylinder and through the other of said closures; a pair of springs surrounding said piston rod, one within said cylinder and one outside said other closure; an adjusting nut on the extremity of said piston rod, adapted for altering the normal rest position of said piston in said cylinder under simultaneous compression of said springs; a bracket mounted at the adjusting end of said

5 cylinder and carrying an adjusting screw adjacent the end of said piston rod and in line therewith, resilient means between said adjusting screw and said adjusting nut; an eccentrically disposed opening through that closure facing said piston, through which gas in said chamber may be evacuated; an axially disposed opening through said same closure; and a self-contained valve assembly disposed in said last-mentioned 10 opening, said valve assembly including a tubular casing extending toward said piston and a valve in said casing having a valve stem protruding from said casing to within a short distance of said piston, said casing being slotted at the piston end thereof.

CHRISTIAN A. SORENSEN.
